GAS BURNER

Robert J. Kehl, Bayside, N. Y., assignor, by mesne assignments, to Union Carbide and Carbon Corporation, a corporation of New York

Application May 6, 1933, Serial No. 669,688

5 Claims. (Cl. 158—99)

This invention relates to gas burners and particularly to an improved gas mixer and means for conducting the combustible gas mixture to the burner tips in combination with means for adjusting the direction of the gas jets.

An object of this invention is to obtain definite but changeable characteristic gas flames and to provide a universal adjustment of the flames about a center within certain limits.

Another object of the invention is to provide a nozzle having two gas passages, one in continuation of the other, and adjustable relatively to one another, wherein there will be no leakage of gas in passing from one passage to the other. These objects together with others will be more evident from the following description and the accompanying drawing, of which

Fig. 1 is a cross sectional view of the mixing device showing one form of mixer for combining or commingling gases.

Fig. 2 is a view of the mixer and burner as assembled showing a number of nozzles adjustably mounted on the header portion of the burner; and

Fig. 3 is a sectional view of an adjustable nozzle, showing the flexible tubing and ball and socket joint.

In mixing gases which produce high temperature flames for heating or cutting purposes it is desirable to control the proportion of combustible and combustion supporting gases in order to obtain a mixture that will be most suitable for a given set of working pressures. For this purpose an injector which has all of the parts and passageways necessary for mixing the gases may be inserted in a unitary body and be used for producing the desired mixture. When the jet or flame is to be changed to meet new working conditions, the change can be effected most readily by interchanging the injector for one having differently sized passageways. By thus changing the internal parts of the mixer, there is no possibility of obtaining unbalanced mixtures of gases such as might occur if the passageways of the injector or the pressures of the constituent gases were varied independently by an operator.

In accordance with this invention a novel device is provided for mixing gases. The device may be supplied with a number of inlet passages through which the gases to be mixed are admitted and with a central nipple or injector for receiving the gases through ports adjacent the inlet openings.

FIG. 1 shows a cross section of the mixing device and FIG. 2 shows the device assembled on a burner. FIG. 3 shows a detail of the nozzle.

The device comprises a unitary body A having an inlet 10 and an inlet 11 arranged on opposite sides of the body and offset one from the other. The casing A is provided with bosses 12 and 13 through which the inlets 10, 11 are drilled and in which threads are cut for receiving nipple connections 14 and 15. A bore 16 is made from the end of the body A near the inlet 10 and extends to a point substantially three-fourths of the distance through the body, at which point the bore 16 is diminished in size to form an outlet 17. The external diameter of the body A may be reduced adjacent the outlet 17 and provided with external threads 18 to serve in making a connection with a burner or with a header H, to be hereinafter described, for conveying gas away from the mixer.

The bore 16 is provided with screw threads which cooperate with threads on a mixing plug B threadedly fitted into the bore. However the member B may be held within the bore in any other suitable manner. The member B may have a hexagonal head 19 for turning the member into place, and a chamfered shoulder 20 may be provided at the base of the head 19 for assisting in sealing off the end of the bore 16 when the member B is tightly forced against a similarly beveled area 21 on the body A adjacent the outer end of the bore 16. The member B has a central passage P which extends to the base of the head 19. The forward portion of the passage P forms a mixing chamber P_m which is conical in shape. The passage P converges from its discharge outlet to a passage of small uniform size which communicates with the inlet 10. The member B is substantially reduced in diameter opposite the inlet openings 10 and 11 so as to form annular chambers 22 and 23 respectively with the bore 16 to admit the constituent gases to all points around the periphery of the reduced portions of the member B. A number of ports 24 are drilled in the member B adjacent the inlet 10 in order to allow gas to pass from the annular chamber 22 into the passage P, and similar ports 25 are drilled adjacent the inlet 11 to allow the passage of gas from the chamber 23 to the passage P. The ports 24, 25 and the passage P form the only means of communication between the chambers 22 and 23, on account of the close interfit between the threads of the member B and the threads of the bore 16, which interfit makes the member B gas tight in the body and prevents leakage between the chambers. The ports 24 and the ports 25 may be proportioned in diameter

50

55

so as to admit the constituent gases at given or predetermined pressures in the amounts required for the mixture that it is desired to obtain in the tapered passage P.

- 5 The gases are thoroughly mixed in the passage P because the gas under pressure entering through the ports 24 has an aspirating effect on the other constituent gas, drawing the latter in through the ports 25. This latter gas, which may also 10 be under pressure as it flows through the ports 25, sets up a turbulent effect in the passage P, and causes an intimate mixing of the gases. In general practice it is preferred to introduce oxygen or other combustion supporting gas 15 through the ports 24 and hydrogen or other combustible gas through the ports 25.

In order to vary the proportion of the gases in the mixture for given regulator pressures, the ratio between the respective combined cross-sectional areas of the passages 24 and 25 may be changed, or if it is desired to affect the volume of the mixture which is delivered, the combined areas of each set of the passages may be altered without varying the ratio between them. To 20 meet any new operating condition which requires a different type of heating or cutting flame, it is necessary only to substitute another nipple or injector for the member B. By changing the character of the flame in this manner the 25 uncertainty of obtaining the proper flame which would be attached to regulating the pressures of the gases or to varying the combined cross-sectional area of one set of passages independently of the other is completely eliminated.

30 A greater number of inlet passages than two may be provided in the body A for supplying several constituent gases, and, correspondingly, an increased number of port openings may be made in the member B adjacent each of the 35 inlet passages for admitting the respective gases to the mixing chamber in the member B.

The mixer A may be connected with a header H which serves as a distributing member to direct the mixed gases to a number of nozzles 40 N, as shown in Fig. 2. The threaded outlet 18 of the mixer is preferably joined by means of a union 30 with an extension fitting and with a nipple 31 which is screwed into a threaded opening 32 in the header H. A chamber 33 for receiving the mixed gases when the valve is open extends longitudinally of the header, being closed off at one end by a suitable plug 34. Leading from the chamber 33 are a number of small transverse passages 35 which are capable of supplying gas individually to the nozzles N and which may be independently controlled by separate control or plug valves 36. The passages 35 and the threaded portions thereof into which the nozzles N are screwed are arranged in a row.

60 In further accord with this invention the nozzles N are so constructed as to be adjustable to any desired position. As shown in Fig. 3, the nozzle N may comprise a nipple or base member 65 40 which is attachable to the header H of a burner or to the outlet of any high temperature gas burning apparatus. The base member 40 has a hemispherical portion 41 at one end which serves as the ball element of a partial ball and 70 socket joint. The rounded portion 41 of the member 40 cooperates with a shell 42 which has a flared shoulder or socket 43 that is maintained or locked in contact with the member 41 in any desired position by a rotatable locking nut 44.

75 Thus, in the example disclosed, each nozzle N

is adjustable laterally in all directions relatively to the axis of the branch passage 35 in the header H with which it communicates. Furthermore the nozzles are independently adjustable by a simple manipulation of the several nuts 44, and they may be positioned in line in the same plane with the passages 35, laterally to either side of that plane, and equal or unequal distances apart. It will also be evident that the nozzles N are easily detachable for repair or replacement without distortion or mutilation thereof, since each nozzle may be screwed into the header H or removed therefrom without interference with any other nozzle.

In order to give ample space for the swinging movement of the shell 42 in relation to the member 40 when the locking nut 44 is loosened, a relatively large opening is made in the end of the nut through which the shell extends, the edges of the opening being rounded so as to permit the shell 42 to be readily positioned. In addition the nut 44 may have a sloping shoulder 45 for clamping the flared end 43 of the shell against the rounded portion of the base member 40. The shoulder 45 may be machined at an angle so as to be substantially parallel with the locus of a tangent to the rounded portion of member 40 in order that the shell may be easily moved when the nut is loosened. An annular space 46 between the base of the threads and the shoulder 45 of the nut insures additional space for the movement of the shell to extreme angular positions, one of which is shown in the drawing.

The shell 42 may be a rigid cylindrical member serving to support a nipple 47 and tip 48 and to encase a flexible tubing or conduit 49, which connects the base member 40 with the nipple 47. The shell 42 is spaced from the flexible tubing 49 and may have a number of openings 50 for admitting air in order to cool the tubing to some degree. In making the flexible tubing 49 into a gas tight conduit, the inlet end of the tubing is fitted within a counterbore 51 in the passage of the member 40 and is silver soldered, as at 52, the solder flowing into a recess in the member 40 and being machined after cooling to maintain the smooth, rounded contour of head 41 for the flared end 43 of the shell 42 to cooperate with. The opposite end of the flexible tubing 49 fits within the nipple 47 as in a sleeve. Solder may be employed to effect tight joints between the tubing and the nipple and also between the nipple and the outer shell 42, thereby making a rigid mounting for the tip 48 which is preferably screwed in a tight manner onto threads 53 provided on the nipple 47. The tip 48 may be a standard nozzle fitting adapted to deliver a jet of gas of the character and volume desired.

A nozzle of the kind described is adjustable in any plane within workable limits. By loosening the nut 44, the tip 48 may be readily moved to direct a jet or flame at any angle against the object to be heated, and by tightening the nut the nozzle is maintained in a rigid, locked position. The fullest advantage may be derived from the adjustability of the nozzles when the nozzles are attached to a header, such as the member H, the position of which is fixed within a machine or upon a mounting (not shown). In such cases the angle of the flames issuing from the nozzles is easily changed by individually adjusting the nozzles.

The burner with adjustable nozzles is especially adapted for working glass. The glaze or polish on the surface may be changed as to

depth and other characteristics by varying the angle at which the flames from the nozzles impinge against the surface.

Although a preferred form of this invention has been described it will be understood that changes may be made without departing from the scope of this invention as defined in the appended claims.

I claim:

10. 1. A nozzle comprising, in combination, a nipple having a bore; a tubular member; an outlet tip secured to said tubular member; a conduit in said tubular member connecting said bore to the entrance of said tip; and adjustable means for clamping said tubular member to said nipple.
20. 2. A nozzle comprising, in combination, a nipple having a bore; a tubular member; an outlet tip secured to one end of said tubular member; said nipple and the other end of said tubular member having cooperating portions formed to provide a ball-and-socket joint; a flexible conduit in said tubular member connecting said bore to the entrance of said tip; and adjustable means for clamping said other end of the tubular member to the cooperating portion of said nipple.
25. 3. A nozzle comprising, in combination, a nipple having a bore, threads at one end of said nipple, and a rounded head at the other end thereof; a tubular member having a flared end cooperating with said head to form a ball-and-socket joint between said nipple and said tubular member; an outlet tip secured to the other end of said tubular member; a flexible conduit in said tubular member connecting said bore to the inlet of said tip; and an adjustable clamping nut cooperating with said threads and engaging said tubular member to clamp said flared end against said rounded head.
4. A nozzle comprising, in combination, a nipple having a bore; an outlet tip adjustable relatively to said nipple and its axis; a flexible conduit connecting said bore and the entrance of said tip; and adjustable means for clamping said tip in any one of a number of different angular positions relatively to the axis of said nipple.
5. A nozzle comprising, in combination, a nipple having a bore; an outlet tip; a flexible conduit connecting said bore and the entrance of said tip; means providing a flexible joint between said tip and said nipple; and adjustable means for clamping said tip to said nipple.
